(57) **CLAIM**

The ornamental design for a lighting fixture, as shown and described.

DESCRIPTION

FIG. 1 is a front left perspective view from below of a lighting fixture according to the new design;

FIG. 2 is a front right perspective view from above thereof;

FIG. 3 is a front elevational view thereof;

FIG. 4 is a right side elevational view thereof;

FIG. 5 is a left side elevational view thereof;

FIG. 6 is a rear elevational view thereof;

FIG. 7 is a top view thereof;

FIG. 8 is a bottom view thereof;

FIG. 9 is a top perspective view thereof;

FIG. 10 is a bottom perspective view thereof; and,

FIG. 11 is a front elevational view of an alternative embodiment of the lighting fixture according to the new design similar to FIGS. 1-10 with break lines indicating a symbolic break and the appearance of any portion of the lighting fixture between the break lines form no part of the claimed design.

The dashed broken lines in the drawings illustrate portions of the lighting fixture that form no part of the claimed design.

The dot-dash broken lines define the bounds of the claimed design and form no part of the claimed design.

1 Claim, 7 Drawing Sheets
